SHEET SORTING MACHINE WITH ELECTRICAL TIMING DEVICE

John F. Peters, Leonia, N. J., assignor to American Can Company, New York, N. Y., a corporation of New Jersey

Application November 6, 1947, Serial No. 784,445

5 Claims. (Cl. 209—74)

1

The present invention relates to a machine for sorting sheets of material moving along a predetermined path of travel through a plurality of sheet sorting stations and has particular reference to devices for delivering a classified sheet into its proper sorting station in accordance with the dimensional or other characteristics of the sheet and the distance of the station from the place of classification of the sheet.

An object of the invention is the provision in a sheet sorting machine of sheet delivery devices wherein delivery of a selected or classified sheet into its proper sorting station is effected in accordance with its dimensional or other characteristics and in accordance with the distance of the station from the place of selection or classification of the sheet so that accuracy of delivery of the sheets may be obtained under high speed operating conditions.

Another object is the provision of such sheet delivery devices wherein the devices operate continuously for smooth and efficient operation and are merely set selectively for delivery of a classified sheet into its proper sorting station.

Another object is the provision of such sheet delivery devices wherein the devices are provided in multiple, arranged one at each station, and operated at different speeds in relation to their distance from the place of classification of the sheets to effect an accurate and reliable time delay action for delivery of a classified sheet into its proper sorting station.

Numerous other objects and advantages of the invention will be apparent as it is better understood from the following description, which, taken in connection with the accompanying drawings, discloses a preferred embodiment thereof.

Referring to the drawings:

Figure 1 is a side elevation of a sheet sorting machine embodying the instant invention with parts broken away; the view including a wiring diagram of the electric apparatus used in the machine;

Fig. 2 is an enlarged sectional detail taken substantially along the line 2—2 in Fig. 1, with parts broken away;

Figs. 3 and 4 are enlarged details of a portion of the machine, illustrating certain of the movable parts in different positions, with parts broken back and shown in section;

Fig. 5 is a top plan view of the machine shown in Fig. 1, with parts broken away;

Fig. 6 is an enlarged detail of a portion of the

timing devices illustrated in Figs. 3 and 4, with parts broken back and shown in section;

Figs. 7, 8, 9, 10 are diagrammatic views illustrating the cycle of operation of the various timing devices used in the machine;

Fig. 11 is an enlarged transverse section taken substantially along the line 11—11 in Fig. 1, with parts broken away; and

Fig. 12 is a top plan view of the portion of the machine shown in Fig. 11.

As a preferred embodiment of the invention the drawings illustrate a machine for classifying or gauging according to thickness, sheets A of tin plate or the like material and for sorting them into classified piles or stacks, although the invention is equally well adapted to machines for classifying sheets otherwise, such as for weight or length or width or hardness or strength, etc., and for sheets of other materials, either metallic or nonmetallic.

In the machine, the sheets A are received from any suitable source of supply of sheets of various thicknesses and are fed one at a time into a classifier or thickness gauge B located at the entrance end of the machine (at the left as viewed in Fig. 1). The thickness gauge B determines the thickness of each sheet as it passes therethrough. After leaving the thickness gauge, the sheets are propelled in a continuous procession along a straight path of travel through a plurality of sorting stations D, E, F, G, having sheet delivery devices H which are controlled by the gauge B and which operate in timed relation in accordance with their distance from the gauge to divert the sheets from their path of travel and deposit them onto stacks J, K, L, M according to their classified thickness.

By way of example, sheets having a thickness below .0075 inch may be diverted onto stack J. Sheets having a thickness of between .0075 and .0088 inch may be diverted onto stack K. Sheets between .0089 and .0099 inch in thickness may be deposited onto stack L. Those having a range of .010 to .0115 inch in thickness may be deposited onto stack M, and all sheets over .0115 inch thickness may be discharged from the far end of the machine (at the right as viewed in Fig. 1) as unclassified and deposited on a miscellaneous stack O.

The classifier or thickness gauge B may be of any suitable type such as that disclosed in United States Patent 2,307,572 issued January 5, 1943 to R. H. Cramer on Gauging and Sorting Machine or in United States Patent 2,219,622 issued October 29, 1940 to D. Bucciccone on Thickness Gauge.

Briefly such a gauge includes a fixed gauging element 21 (Figs. 1 and 2) and a yieldable gauging element 22 between which the sheet is interposed for gauging. The yieldable gauging element is carried on a movable member 23 which actuates a movement amplifying arm 24 which also serves as an electric contact arm for making electrical contact selectively and in accordance with the thickness of a sheet being gauged, with any one of a plurality of contacts 26, 27, 28, 29 (Fig. 1) of electric control circuits which will be hereinafter explained in connection with the wiring diagram and which are utilized to divert a gauged sheet into position on its proper stack as hereinbefore mentioned. Such a gauge is carried on a bracket 31 bolted to a long frame 32 which constitutes the main frame of the machine.

The sheets A are propelled through the machine, including the thickness gauge B, in a horizontal flat position, by an endless chain conveyor 35 which extends the full length of the machine, through the sorting stations D, E, F, G. This conveyor is provided with spaced feed dogs 36 for propelling engagement behind the sheets. The conveyor operates over an idler sprocket 37 and a driving sprocket 38. The idler sprocket is mounted on a cross shaft 39 journaled in a bearing bracket 41 secured to the main frame 32 at the feed-in or entrance end of the machine. The driving sprocket 38 is mounted on a drive shaft 43 journaled in a bearing bracket 44 secured to the main frame at the discharge end of the machine.

The conveyor 35 is operated continuously by a chain and gear connection with a continuously rotating main shaft 45 (Figs. 1 and 5) which extends along one side of the main frame 32 and which is journaled in a plurality of spaced bearing brackets 46 secured to leg sections 47 of the frame. For this purpose the sprocket drive shaft 43 carries a driving sprocket 51 which is driven by an endless chain 52 from a driving sprocket 53 carried on the outer end of a short shaft 54 journaled in the bearing bracket 46 at the discharge end of the machine. The inner end of the short shaft 54 carries a bevel gear 56 (see Fig. 5) which meshes with and is driven by a bevel gear 57 mounted on the end of the main shaft 45. The main shaft may be rotated in any suitable manner, and at a rate of speed of one revolution for each sheet A fed through the gauging device B.

During passage of the sheets A through the machine, they are supported in their horizontal flat position on a table 61 (Fig. 5). This table comprises a plurality of spaced and parallel slats 62 which extend longitudinally of the machine in short sections providing a transverse space 63 (see also Figs. 3, 4, 12) at each of the sorting stations D, E, F, G adjacent the leg sections 47 of the main frame 32. These slats are secured to crossbeams 64 which constitute transverse members of the main frame. Longitudinal side guides 65 (see also Figs. 11 and 12) secured to the main frame along opposite sides of the path of travel of the sheets maintain the sheets in a straight line as they pass through the machine.

The transverse spaces 63 in the table 61 provide outlets through which the gauged sheets may be diverted to the stacks J, K, L, M, at their respective sorting stations D, E, F, G as hereinbefore mentioned. Diversion or deflection of the sheets through these spaces 63 is effected by gates 68 which are disposed within the spaces and which form part of the sheet delivery devices

H. There is one of these gates 68 for each space 63.

The gates 68 comprise a plurality of short flat cantilevers 69 which are disposed in line with the table slats 62 and which form movable continuations thereof. The top surfaces of these cantilevers are normally flush with the top surfaces of the slats 62 to facilitate travel of the sheets along the table 61. These cantilevers are mounted on rockshafts 71 which extend across the machine and which are carried in bearings 72 (see Figs. 11 and 12) formed in the main frame 32. There is one of these rockshafts for each gate 68.

15 Along one side of the machine, as viewed in Figs. 1 and 5 each rockshaft 71 carries a gate actuating arm 75 (see Figs. 3, 4, 11 and 12) which extends down adjacent the path of travel of a reciprocating latch finger 76 mounted on a pivot pin 77 carried in collar 78 clamped onto a slide bar 79. The bar is supported in slide bearings 81 formed on the leg sections 47 of the main frame 32. There is one latch finger 76 located at each sorting station D, E, F, G and they are all mounted on and reciprocated simultaneously by the slide bar 79 in time with the passage of the sheets A through the machine.

Reciprocation of the slide bar 79 is effected by a vertically disposed lever 83 (Fig. 1) which is located at the discharge end of the machine and which is mounted on a pivot pin 84 carried in a bracket 85 bolted to the leg section 47 of the frame at the discharge end of the machine. The upper end of the lever is bifurcated and straddles a grooved collar 86 secured to the slide bar. The lower end of the lever carries a cam roller which operates in a cam groove 87 of a barrel cam 88 mounted on and rotating with the main shaft 45.

40 The slide bar 79 makes one reciprocation which includes a forward or working stroke and a return stroke, for each sheet A fed through the gauging device B. Upon each forward stroke (toward the left as viewed in Figs. 1, 3, 4 and 5) of the slide bar 79, the latch fingers 76 move along a path of travel extending alongside of the gate actuating arms 75 but do not engage the arms unless they are shifted inwardly toward the arms. This lateral shifting of a latch finger 76 is effected only when a gauged sheet is to be diverted at the particular sorting station at which the shifted latch finger is located.

45 Lateral shifting of a latch finger 76 is brought about through a shift plate 91 (Figs. 1, 3, 4, 11 and 12) disposed adjacent the path of travel of the latch fingers 76. There is one of these shift plates 91 for each finger and these plates guide the fingers during their reciprocating movement. For this purpose each finger 76 carries a roller 92 (Fig. 12) which rides on the inner surface of its cooperating shift plate 91. The roller is maintained under pressure in position against the plate by a compression spring 93 which is interposed between the back of the latch finger and a support lug 94 formed on the adjacent collar 78.

50 The shift plates 91 are formed on the outer ends of plate arms 96 (Figs. 11 and 12) which are mounted on pivot pins 97 carried in the main shaft bearing brackets 46 bolted to the frame legs 47. The arms are held under spring pressure by a tension spring 101. One end of the spring is connected to a pin 102 which depends from the arm and the other end of the spring is connected by a pin 103 to the frame leg 47. A 55 lug 104 projecting out from the frame leg en-

gages the spring pin 102 and limits the outward movement of the plate arm 96.

Each plate arm 96 is formed with an angularly disposed trip lever 108 which extends outwardly adjacent a timing device 109. There is one timing device for each sorting station D, E, F, G and each device includes a rotatable trip drum 111 mounted on one end of a short shaft 112 journaled in a bearing 113 formed in the bearing brackets 46.

The shafts 112 are continuously and independently driven at different rates of speed in accordance with the distance of the sorting station from the gauging station. For this purpose each of the shafts 112 carries a gear 115 which meshes with and is driven by a cooperating driving pinion 116 mounted on the main shaft 45.

There is one pinion 116 and one gear 115 for each trip drum 111. At the first sorting station (D) the pinion and the gear are of equal diameters thus making the ratio 1 to 1. Hence at this station the trip drum is rotated at the same speed as the main shaft 45 and makes one revolution for each sheet A since this station is located a distance equal to one sheet away from the gauging station. At the second sorting station (E) the gear ratio is 2 to 1, the gear being twice the diameter of the pinion. Hence the drum at this station rotates one half the speed of the main drive shaft 45 and makes one half a revolution for each sheet A, since it is two sheets distant from the gauging station. Similarly the gear ratio at sorting stations F and G are 3 to 1 and 4 to 1 respectively, thus driving the drums at these stations at one third and one quarter respectively of the speed of the main shaft. Hence the drums at these stations make respectively one third and one quarter revolutions for each sheet A since they are three and four sheets distant from the gauging stations.

Each of the trip drums 111 carry trip pins 118 (see Fig. 6) which are slidably disposed adjacent the periphery of the drums in transverse bores 119 extending through the drums from one side to the other and which project beyond the drum on the side opposite the trip levers 108 as best shown in Fig. 4. The drum at sorting station D carries one of these trip pins 118 diagrammatically illustrated in Fig. 7. The drum at station E carries two pins located in diametrically disposed relation as in Fig. 8, and the drums at stations F and G carry three and four pins respectively as shown in Figs. 9 and 10.

As the drums 111 rotate, the projecting ends of the pins 118 move past a depending leg 122 (Figs. 3, 4, 6 and 11) of a bell crank timing lever 123 connected to and actuated by a movable element 124 of a normally de-energized electric solenoid 125. There is one of these solenoids for each sorting station D, E, F and G and they are carried on flat plates 126 which are bolted onto the slide bar bearings 81 formed on the main frame 32. The bell crank lever for each solenoid is mounted on a pivot pin 127 carried in a pair of lugs 128 (Figs. 6 and 11) formed on the support plates 126.

Each of the solenoids 125 are connected electrically with the gauging device B and are energized and de-energized selectively in accordance with the thickness of a sheet passing through the gauging device. For this purpose the gauging device B is connected by a wire 131 (Fig. 1) to a source 132 of electric current which in turn is connected to a main lead wire 133 having wires 134, 135, 136, 137 leading therefrom to the four solenoids 125 respectively. In a simi-

lar manner the four solenoids are connected by separated wires 138, 139, 140, 141 to the respective electric contacts 26, 27, 28, 29 of the gauging device B.

Hence when a sheet A passes between the fixed element 21 and the yieldable gauging element 22 of the gauging device B, the yieldable gauging element 22 is raised or otherwise shifted in accordance with the thickness of the sheet and thereby causes one of the contacts 26, 27, 28, 29 through the medium of the gauge amplifying arm 24 to be connected with the source 132 of electric current. An electric circuit is thereupon immediately established through the solenoid 125 connected with the closed contact and this immediately energizes the solenoid. The circuit is maintained for as long a period of time as the sheet remains in the gauging device B and is broken as soon as the sheet leaves the gauging elements 21, 22.

Energization of a solenoid 125 immediately depresses its movable element 124 (Fig. 6) and this rocks the bell crank timing lever 123 so that its depending leg 122 engages against the projecting inner end of the trip pin 118 at station D (or one of the trip pins 118 in the case of all of the other timing devices) and thus pushes the engaged pin outwardly so that its outer end will project beyond the outer face of its trip drum 111 adjacent the trip lever 108 of this timing device as shown in Fig. 4. This engagement of the trip pin 118 takes place at a predetermined place in its cycle of travel with its drum 111 and is synchronized with the operation of the gauging device B so that the pin 118 will always be in the same place at the time the solenoid 125 is energized. This predetermined place of engagement is different for each timing device 109, as schematically illustrated by the full line pins 118 shown in Figs. 7, 8, 9 and 10, in order that the depending legs 122 of the timing devices 109 engage the pins 118 when the latter are at their proper places of engagement. As for example the leg 122 at the sorting station D is curved as shown in Fig. 11 and terminates opposite the pin 118 shown in that figure. If desired the solenoids may be located at these predetermined places of engagement instead of in the straight line arrangement shown in the drawings and the legs 122 all made short and straight as in the case illustrated in Fig. 10 which represents the sorting station G.

In any case, a trip pin 118 which has been "set," by being shifted so that its outer end projects beyond the outer face of its drum 111 travels with the drum during its rotation and engages against and lifts the adjacent trip lever 108 at the sorting station adjacent the energized solenoid after a predetermined length of time in accordance with the distance of the sorting station from the gauging station and after the sheet has been gauged at the gauging station.

In the case of the first station D this engagement takes place immediately as disclosed by reference to Fig. 7. In the case of the second station E this engagement takes place after the set pin 118 has traveled through one half a revolution of its drum 111 as shown in Fig. 8. At stations F and G this engagement takes place after two thirds and three quarters respectively of a revolution of the drums 111 as shown in Figs. 9 and 10. This timing is brought about by the timing gears 115, 116.

The engagement of a set pin 118 with its trip lever 108 forces the trip arm 96 at a station in-

wardly, and thus pushes the latch finger 76 at this station inwardly into alignment with the gate actuating arm 75 located at this same station. This inward movement of the latch finger 76 takes place as it is moving forward through a working stroke of the slide bar 79.

Hence with the latch finger held in this position by engagement of the "set" pin 118 with its trip lever 108, it engages and rocks the gate actuating arm 75 and thereby raises the gate cantilevers 69 just as the gauged sheet A traveling along the table 61 approaches the sorting station D, E, F or G having the timing device which the gauging device B has energized. This raising of the cantilevers 69 at a station brings them into the position shown in Fig. 4 and thus deflects the approaching sheet from the table 61 to one of the stacks J, K, L, or M as shown in Fig. 4. The stacks preferably are arranged on skids 145 so that the gauged stacks of sheets may be readily removed to any suitable place of deposit.

As soon as a gauged sheet A has been diverted from the table 61 to its place on the proper stack J, K, L, or M, the slide bar 79 starts back through a return stroke and thus permits the raised cantilevers 69 to move down into their normal closed position. During this return stroke of the slide bar 79, the "set" pin 118 rides off the trip lever 108 and this permits the lever and its associated trip arm 96 to fall back under the tension of the spring 101. This also releases the latch finger 76 and permits it to move outwardly away from the path of travel of the gate actuating arm 75 where it is in readiness for a repeat movement for the next sheet A which is to be diverted at this station.

As a "set" pin 118 rides off its trip lever 108 it is shifted back into its normal position out of the way of the trip lever, with its inner end projecting from the inner face of its drum 111. This is effected by a stationary reset cam 147 (Fig. 11) which projects downwardly from the solenoid support plate 126 on the main frame 32 and extends adjacent the drums into the path of travel of the pin 118. There is one of these reset cams 147 for each drum 111 and they are engaged by the pins as the latter pass them for pushing them back into place.

In this manner, each sheet A as it enters the gauging device B, energizes the solenoid 125 of one of the sorting stations D, E, F or G which corresponds to the thickness of the sheet and thereby "sets" a continuously operating time delay or timing device 109 so that when the sheet after being gauged reaches that particular station it will be diverted onto a stack of sheets having the same thickness range.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for sorting sheets of material in accordance with their dimensional or other characteristics, the combination of a gauging device through which the sheets are fed one at a time, a conveyor for propelling the gauged sheets along a predetermined path of travel through a plurality of sheet sorting stations disposed at

various distances from said gauging device, sheet diverting means at each of said sorting stations for diverting a gauged sheet from said path of travel, timing mechanisms located at each of said sorting stations and having trip devices increasing in number substantially proportionately with the distance of each timing mechanism from said gauging device, said trip devices being controlled selectively by said gauging device for actuating said diverting means, and means for actuating each of said timing mechanisms at a different rate of speed relative to the speed of travel of the sheets propelled by said conveyor and in accordance with the distance of the timing mechanisms from said gauging device.

2. In a machine for sorting sheets of material in accordance with their dimensional or other characteristics, the combination of a gauging device through which the sheets are fed one at a time, a conveyor for propelling the gauged sheets along a predetermined path of travel through a plurality of sheet sorting stations disposed at various distances from said gauging device, sheet diverting means at each of said sorting stations for diverting a gauged sheet from said path of travel, a rotatable timing drum located at each of said sorting stations and controlled selectively by said gauging device, each of said timing drums having protractable timing pins increasing in number substantially proportionately with the distance of the drum from said gauging device for actuating said diverting means, and means for actuating each of said timing drums at a different rate of speed relative to the speed of travel of the sheets propelled by said conveyor and in accordance with the distance of the timing drums from said gauging device.

3. In a machine for sorting sheets of material in accordance with their dimensional or other characteristics, the combination of a gauging device through which the sheets are fed one at a time, a conveyor for propelling the gauged sheets along a predetermined path of travel through a plurality of sheet sorting stations disposed at various distances from said gauging device, sheet diverting gates at each of said sorting stations for diverting a gauged sheet from said path of travel, continuously reciprocating means disposed adjacent said gates and operating in time with the travel of said sheets propelled by said conveyor, trip elements disposed adjacent said reciprocating means and effecting actuation of said gates through said reciprocating means, timing devices located at each of said sorting stations and controlled selectively by said gauging device for actuating said trip elements, and means for actuating each of said timing devices at a different rate of speed relative to the speed of travel of the sheets propelled by said conveyor and in accordance with the distance of the timing devices from said gauging device.

4. In a machine for sorting sheets of material in accordance with their dimensional or other characteristics, the combination of a gauging device through which the sheets are fed one at a time, a conveyor for propelling the gauged sheets along a predetermined path of travel through a plurality of sheet sorting stations disposed at various distances from said gauging device, sheet diverting gates at each of said sorting stations for diverting a gauged sheet from said path of travel, actuating arms on said gates, a continuously reciprocating slide bar disposed adjacent said gate actuating arms and operating in time

with the travel of said sheets propelled by said conveyor, a latch finger for each of said gate actuating arms, said latch fingers being movable by said bar along a path of travel adjacent said arms, trip levers disposed adjacent said arms and engageable selectively with said latch fingers for shifting the fingers into engagement with said arms for actuating said gates selectively, timing devices located at each of said sorting stations and controlled selectively by said gauging device for actuating said trip levers, and means for actuating each of said timing devices at a different rate of speed relative to the speed of travel of the sheets propelled by said conveyor and in accordance with the distance of the timing devices from said gauging device.

5. In a machine for sorting sheets of material in accordance with their dimensional or other characteristics, the combination of a gauging device through which the sheets are fed one at a time, a conveyor for propelling the gauged sheets along a predetermined path of travel through a plurality of sheet sorting stations disposed at various distances from said gauging device, sheet diverting means at each of said sorting stations for diverting a gauged sheet from said path of travel, reciprocating latch means at each sorting station and having continuous movement ad-

5 jacent each of said sheet diverting means, each latch means being selectively engageable with its associated sheet diverting means by lateral movement of the latch means, timing devices located at each of said sorting stations adjacent each of said latch means, said timing devices being controlled by said gauging device to selectively move a latch means into engagement with its said diverting means in accordance with the gauging of the sheet, and means for actuating each of said timing devices at a different rate of speed relative to the speed of travel of the sheets propelled by said conveyor and in accordance with the distance of the timing devices from said gauging device.
